TAPE MAGAZINE FOR SHOE MACHINERY

Philip L. O'Donnell, Norwood, Ohio

Application March 21, 1938, Serial No. 197,080

5 Claims. (Cl. 112—2)

This invention relates to a tape holding appliance for use with a shoe sewing machine and particularly for use with those machines in which reinforcing tape and French binding are applied at the same time by one operation of said sewing machine, for example, as shown in Gerber Patent 1,466,937.

An object of the invention is to provide a simple, compact and efficient magazine for the reinforcing tape, from which said tape may be taken as needed.

A further object of the invention is to provide suitable enclosed tape guide means between the tape magazine and a point adjacent the conventional tape guide located upon the work support of the sewing machine.

A further object of the invention is to provide a suitable enclosed tape guide through which reinforcing tape, which has one surface coated with an adhesive substance, may be led from the tape magazine to the tape guide without subjecting the adhesive side of said tape to contact with said guide.

Still a further object of the invention is to provide a tape magazine which may be mounted flat upon the table of a sewing machine, and which may be easily refilled when empty and further, which has a suitable aperture in the lid thereof whereby the quantity of tape in said magazine may be ascertained at a glance, by the operator.

Another object is to provide a device of the character referred to, wherein the parts are so related that the adhesively coated tape is withdrawn from the roll or supply of tape, in such manner as minimizes the effect of the adhesion of contacting layers or convolutions of the tape. Thus the characteristics inherent in the tape, are availed of for causing the tape to separate from the roll and accordingly the tape is free of tension as it is applied to the shoe or other part, by instrumentalities of the type shown in said Gerber patent.

These and other objects are attained by the means described herein and disclosed in the accompanying drawing, in which:

Fig. 1 is a side plan view of a device embodying the invention, in operative position relative to parts of a machine of the character shown in Gerber Patent 1,466,937.

Fig. 2 is a top plan view of parts shown in Fig. 1 showing the magazine lid in open position.

Fig. 3 is a cross sectional view taken on line 3—3 of Fig. 2.

Fig. 4 is a cross sectional view taken on line 4—4 of Fig. 2.

Fig. 5 shows a top plan view of the magazine with the lid in closed position.

Fig. 6 is a side view of the tape guide.

Fig. 7 is a top view of the tape guide showing the protective shield 41 in open position.

Fig. 8 is a fragmentary elevational view showing the independent tape tension relieving mechanism embodying a modified form of the invention.

Fig. 9 is a plan view of one type tape release wheel forming a detail of the invention.

Fig. 10 is a plan view of a modified form of a tape release wheel.

It is customary in the manufacture of women's shoe uppers to apply a French binding to the top edge and at the same operation to apply a reinforcing tape to the opposite side of said upper.

20 The French binding is used to give a finished appearance to the shoe whereas the binding is used to prevent stretching of the leather and to generally reinforce the edges of the thin materials used for women's shoes.

25 The reinforcing tape is fed beneath the shoe upper through a tape guide positioned on the work support, such as the one disclosed in the patent to Gerber 1,466,937.

The side of the reinforcing tape which is sewed next to the leather or fabric comprising the shoe upper is coated with a non-drying gum adhesive. By reason of said adhesive substance, the entire width of the reinforcing tape is secured in place, although but one edge is actually stitched to the shoe upper.

30 It is to provide a suitable storage magazine for the adhesive reinforcing tape and a suitable enclosed guide leading from said magazine to the tape guide in which the sewing is done that this invention is directed.

35 As shown in Fig. 1, 10 represents a stitching machine work support or standard, suitably mounted upon work board or table 11. To the top of work support 10 a suitable tape guide 12 is mounted (Fig. 2). A tape magazine 13 is mounted flat upon said work board 11. Said magazine comprises an outer circular housing 14 having a U-shaped channel-way 15 formed integral therewith and extending tangentially therefrom. A

40 freely rotatable plate 16 is mounted upon axle 17 which is suitably fastened to housing 14 by any suitable means such as by welding. Axle or pin 17 has a collar 18 formed integral therewith 45 which functions as a bearing surface for sleeve 19

which extends through plate 10 and terminates in a collar 119. In this manner the frictional resistance of plate 16 is reduced to a minimum, as it rotates within housing 14. Plate 16 is held in place by washer 20 and nut 21 (Fig. 3). A suitable shoulder 22 is provided on plate 16 for centering roll 23 of adhesive tape. A suitable lid 24 hinged as at 25 to housing 14 completes the tape magazine. A window 26 of transparent material is provided through lid 24 as shown in Fig. 5. This window is located so as to enable the machine operator to be able to ascertain the quantity of tape in the magazine, at a glance. Such information is quite important to an operator in a shoe factory since to run out of tape while in the process of sewing an upper necessitates a delay while the partly sewed upper is removed from the stitching machine in order that the tape and French binding may be ripped off.

A suitable L-shaped tape channel 30, comprising a horizontal leg 31 and vertical leg 32 is positioned between tape magazine 13 and the machine tape guide 12 mounted on work support 10. Channel 30 may be constructed by cutting through three sides of square stock and by making a right angle bend in the fourth side whereby a channel member, as shown in Fig. 1, is obtained. As shown in Fig. 4, a slit 33 is provided longitudinally of said channel member whereby tape may be easily threaded through legs 31 and 32 by slipping the tape into the interior of the channel sideways through slit 33. A suitable bracket 34 suitably fastened to vertical leg 32 is used to attach said leg firmly to the work support 10 by any suitable means such as by screws 35. The horizontal leg 31 fits into the U-shaped channel-way 15 (Figs. 2 and 4). A suitable roller 36 is vertically mounted within the magazine end of channel leg 31 (Figs. 2 and 6), and a similar roller 37 is mounted in the lower end of vertical leg 32 having its axis in a horizontal plane relative to the first roller 36 and at right angles thereto. A third roller 38 having a concave central portion is mounted adjacent the upper discharge end of leg 32 having its axis in a horizontal plane but at right angles with roller 37.

In use a length of tape 39 is unwound from roll 23 and threaded through channels 31 and 32 as follows: the adhesive side of tape 39 is adjacent the roll 23. Said tape is led off of roll 23 around roller 36 with the adhesive side away from said roller. The tape is turned ninety degrees as it passes through leg 31 so as to pass around roller 37 with the adhesive side away from said roller. Said tape is turned another ninety degrees as it passes up through leg 32 and over roller 38 from which it is delivered with the adhesive side uppermost. As shown in Fig. 6 the upper or discharge end of leg 32 terminates in a tip 40 which has hingedly mounted thereto a cover plate 41 which is capable of being pivoted about screw 42 in order to facilitate the threading of tape from leg 32 into tape guide 12. When in closed position plate 41 serves to protect the upper adhesive surface of the tape by shielding said tape up to within a fraction of an inch of the tape guide unit 12. In this way the possibility of the adhesive surface collecting dust, cloth and thread particles as it is unreeled from a tape roll and led to guide unit 12 is entirely eliminated, thereby enabling an operator to work with greater speed and freedom not having to worry about the condition or presence of the said adhesively coated reinforcing tape.

By conducting the adhesively coated reinforce-

ing tape from the magazine to the guide unit on the machine through the enclosed channels as set forth, greater safety is obtained since the possibility of the material being stitched upon the machine being caught up by the adhesive substance and pulled under the needle, is prevented.

The advantages presented by such a device are obvious since it provides a visible, easily loaded tape magazine having an enclosed tape guide channel which protects the tape from the time said tape leaves the roll until it is presented within the tape guide to be sewed in place on a shoe upper.

The channel member is compact and does not interfere in any way with the operation of the machine, nor with the feeding of the work through the sewing machine since the cover plate 41 presents a smooth surface. By fastening the magazine to the table 11 the unit is rigidly positioned flat against the work table in such a way that work may be piled upon it without lessening the effectiveness of the unit in any way.

Attention is directed to the line x—x in Fig. 2. It will be noted that such line extends through the axis of the plate 16 and tape roll 23 and adjacent the surface of the roller 36. The tape, coated on its inner surface with a so-called "cold adhesive," must turn or bend at about ninety degrees, or substantially along line x—x in order to pass over the roller 36. The cold adhesive causes the outer layer of tape to adhere to the next lower layer of tape, so that ordinarily some power is necessary to detach the outer layer of tape as the tape passes to the roller 36. The tape, while generally quite flexible, has an inherent character of resisting lateral bending. Consequently, since bending of the tape at ninety degrees or exactly along line x—x would meet a substantial resistance to bending, on the part of the tape, the tape will more readily flex along the curved line shown at 50 of Fig. 2. Thus the resistance of the tape toward bending, slight though it may be, is utilized for facilitating and expediting separation of the tape from the roll, immediately prior to the passage of the tape to the feed channel or duct 30. Thus there is always provided a small length of tape, approximating the distance from line x—x to the place 51, at which place the tape leaves or separates from the roll, and which small amount of free tape assures feed of the tape, free of any tension, to the machine parts associated with the standard 10. This feature is very important for the reason that any strain or tension applied to the tape, as it is laid upon the shoe upper, tends to wrinkle or distort the shoe upper. In actual practice, the free length of tape is slightly less than is shown at 50—51 of Fig. 2, the relationship being shown somewhat exaggerated for the purpose of clarity of explanation. If a rather heavy or stiff tape should be used, the relationship would approximate that shown at 50—51, however, with women's shoes, effort is directed toward the use of the lightest materials, for reinforcement, without seriously impairing the ultimate objective of producing a form or shape retaining shoe.

Shoe uppers for women's shoes are made of rather expensive materials, and therefore every effort is made to avoid waste of any uppers for any reason whatsoever. The shoe parts are sent through a factory in lots, each calculated exactly and these parts originate in various parts of the plant. Any interference with production or

damage of parts of such lots therefore involves loss of considerable time of employees, as well as loss of materials. Accordingly, the positioning of the magazine and the window 26 thereof, immediately or substantially beneath that portion of the work support 10 at which an operator feeds material to the work support, makes it possible for the operator to at all times observe the condition of the tape supply and thus avoid feeding of an upper to the machine at a time when the tape supply is inadequate to complete the particular upper about to be worked upon. In this regard, it will be observed that as the tape roll decreases in diameter, the portion of the tape, extending from the tape roll to the roller 36, extends almost diametrically beneath and across the window 26, or approximately along line y—y of Fig. 5.

The disc 16 is intended to have a practically frictionless mounting, so that a minimum of power is required for rotation thereof with the tape roll. The weight of the tape roll on the disk, is sufficient to cause the disc to revolve with the tape roll.

The roll of tape or material 23 is so positioned on the substantially frictionlessly mounted disc, that the portion of such tape, leaving the chamber and extending to the discharge passage thereof, extends at approximately right angle to the discharge passage. That relationship is substantially maintained during the entire period of feed or discharge of the tape from the magazine. While such angle will vary slightly between an acute and an obtuse angle, passing through a right angle condition, such angles are at all times of appreciable divergence in excess of a forty-five degree angle. By leading the tape to the channel, at an angle, as contrasted with taking the tape from the roll on a line tangential to the outer edge of the tape as would be the case if the roll were reversed so the disc would revolve in counterclockwise direction, it is possible to bring the uncoated or back side of the tape into contact with the roller 26, thus avoiding any friction or hindrance to the movement or feed of the tape by reason of contact of the adhesively coated side of the tape with any portion of the apparatus prior to contact thereof upon the work at the top of the standard 10.

It was previously explained that the tape should be fed to the work support, substantially free of tension. This is desirable because any tension that must be overcome, must ordinarily be taken care of by the feed means of the sewing or tape applying mechanism. When any burden is imposed on such feeding means, additional to that for which they are designed, various objectionable developments make themselves evident.

Wrinkling of the material worked is one of such objectionable developments. In view of the fact that in some instances the adhesive used on the tape may be too tenacious to permit ready separation of the outer convolution of tape, from the roll, there may be provided suitable power actuated means, for effecting release of the outer convolution of tape, adjacent the tape receiving end of the channel 30. One form of device for performing such function comprises a tape tension relief wheel, shown at 70 of Fig. 2. The dotted line 90 shows substantially the position that the tape assumes, when relief wheel 70 is interposed between the tape roll 23 and the roller 36. In such modification of the invention, the roller 36 may be omitted, if desired. Regardless of whether a roller such as 36 is used, the tape

release wheel 70 would operate, whenever the sewing and tape applying machine 10 would operate. To attain that end, the wheel 70 is mounted on the motor shaft 14 of electric motor 73 and motor 73 is so connected with the customary electric motor used for operating the stitching machine 10, that operation of customary treadle or other means for making and breaking the circuit of the motor for machine 10 would likewise close and open the circuit embracing the motor 73.

The tape feed wheel 70 comprises a cylindrical shaft having its circumference serrated or roughened in any suitable manner, for example, by vertical file marks 71 (Fig. 9). An alternative form of tape feed wheel as shown in Fig. 10 comprises an elongated member 72 which will impart whipping motion to the tape 39, which will cause the tape to be effectively freed from the supply roll 23.

As shown in Fig. 8, tape feed wheel 70 has an independent motor drive comprising electric motor 73 and shaft 14. This unit may be quickly and easily installed to the tape magazine just described by drilling a hole 75 through work support table 11 and through the bottom of the circular housing 14 whereby a tape feed wheel 70 may be inserted therethrough as shown. The motor 73 is held securely in place by means of suitable strap members as 76, the free ends of which are secured to the underneath side of the table 11 by any customary or suitable means, not shown.

Motor 73 is controlled by the same unit by which the operator controls the operation of the machine. This unit (Fig. 1) comprises a lever 77 which is actuated by the knee of the operator.

As lever 77 is moved to the left, power transmission control shaft 78 is rotated whereby the sewing machine is connected to the power source. A suitable switch 79, mounted on a suitable bracket 80, is positioned adjacent control lever 77 whereby switch actuating pin 81 will be depressed as lever 77 is moved to the left, with the result that the circuit to electric motor 73 is closed. This starts up motor 73 and its associated tape feed wheel 70 so that a short length of tape 39 is separated from supply roll 23 whenever the tape contacts the tape feed wheel. When the operator releases lever 77 the sewing machine and tape feed mechanism stop simultaneously.

It should be understood that any type of machine control may be used in lieu of the knee operated lever 77 shown in Fig. 1. Also, the use of power means other than electric motors may be availed of for attaining substantially the same cooperation of parts, explained herein and accordingly the invention is not limited to electric motor power supply means.

What is claimed is:

1. In combination with a stitching machine adapted to be mounted upon a work table; and comprising an elevated work support member and a tape guide mounted upon said work support, of a tape magazine mounted on said work table adjacent said work support member, and an L-shaped tape delivery channel extending between said magazine and tape guide, said tape magazine comprising a flat housing comprising a base and cylindrical side walls and having formed integrally with said bottom and side walls a U-shaped channelway communicating with and extending tangentially therethrough, a lid having a window disposed therethrough whereby the

interior of said magazine may be observed without necessitating the opening of said lid member which is hingedly mounted to the side wall, a revolute turn table centrally disposed within said magazine on which a roll of tape to be paid out through said channel is mounted, said L-shaped channel member comprising a horizontal leg, the free end of which fits into the U-shaped channelway of the magazine, and a vertical leg which is anchored to the stitching machine work support member, the free end of said vertical leg terminating in close proximity with said tape guide, said L-shaped channel having suitable roller means disposed within its walls whereby tape from the magazine is conducted to said tape guide free from contact with the walls of said channel.

2. In a device of the class described the combination with a power actuated machine for applying adhesively coated tape to an article worked on by said machine, of a magazine for rolled adhesively coated tape including means operable in conjunction with the operation of said machine for contacting the uncoated side of said tape and for separating tape from a roll thereof contained within said magazine, incident to feed of the tape to said machine.

3. In a device of the class described the combination with a power actuated machine including a manual machine-control unit, for applying adhesively coated tape to an article worked on by said machine, of a magazine for housing a roll of adhesively coated tape, means disposed within said magazine for causing the outer layer of adhesively coated tape to separate from the roll incident to discharge from said magazine, said means being under the control of the manual machine-control unit whereby said means is concurrently operative with said power actuated machine.

4. In combination with a stitching machine adapted to be mounted upon a work table, and comprising a work support member and a tape

guide mounted on said work support, of a tape magazine mounted on said work table adjacent said work support member and a tape delivery channel extending between said magazine and tape guide, said tape magazine comprising a flat housing comprising a base and cylindrical side walls and having formed integrally with said bottom and side walls a U-shaped channelway communicating with and extending tangentially therefrom, a revolute turn table centrally disposed within said magazine on which a roll of tape to be delivered to said tape guide through said delivery channel member is mounted, said channel member comprising opposite ends, one end of which fits into the U-shaped channelway of the magazine, the opposite end of said channel member terminating in close proximity with said tape guide, and suitable means disposed within said channel member whereby tape from the magazine is conducted to said tape guide free from contact with the walls of said channel.

5. In combination with a stitching machine adapted to be mounted on a work table and comprising a work support, stitch forming and work feeding mechanisms, of a tape supply reel, an open topped magazine for housing said reel mounted on said work table, a cover member carried by and hingedly mounted to said magazine for controlling access to said reel, a transparent window provided in said cover member for exposing at least a sector of the tape disposed on said reel during those periods of time when the cover member is closed upon the magazine, a tape-discharge channelway provided in said magazine, a tape distribution channelway extending between the tape-discharge channelway of said magazine and said work feeding mechanism, and means associated with said distribution channel for spacing the tape from the walls of the distribution channelway as it moves therethrough incident to the operation of the machine.

PHILIP L. O'DONNELL.
